Inventor:
John N. Koch,
by John Elias Jones,

Attorney.

UNITED STATES PATENT OFFICE.

JOHN N. KOCH, OF CINCINNATI, OHIO.

PHOTOGRAPH CABINET OR RACK.

No. 873,379.

Specification of Letters Patent.

Patented Dec. 10, 1907.

Application filed July 26, 1906. Serial No. 327,821.

To all whom it may concern:

Be it known that I, JOHN N. KOCH, a citizen of the United States, and a resident of Cincinnati, in the county of Hamilton and State of Ohio, have invented a certain new and useful Improvement in Photograph Cabinets or Racks, of which the following is a specification.

This invention relates to certain improvements in boxes or cabinets for use in containing photographs, cards and the like and presenting them to view therein, and it consists in a base, a rack pivotally-supported upon said base and having transverse rods or bars arranged in a parallel series, one or more clips or clasps supported upon or attached to said transverse rods and adapted to receive and support cards, photographs or the like in convenient position for housing and presentation to view.

Other features of the invention will be fully hereinafter described and particularly set forth in the claims.

In the accompanying drawings, which serve to illustrate my invention,—Figure 1 is a perspective view of my improved photo box or cabinet in its preferred form, the top lid thereof being shown open, part-way back, the front wall shown thrown forward on its pivots and the rack supported in inclined position for presenting the photos or other matter to view; Fig. 2, a rear fragmentary portion of the photo supporting-rack, showing the parallel transverse bars and the clips thereon, together with the photos that are inserted in said clips, in cross-section, such photos being canted or leaned against an easel-support, the latter resting against the rear cross-bar of said rack; Fig. 3, a fragmentary plan view of one of the side walls of the casing or box, one of the side bars of the rack, one of the transverse rods of the rack, such transverse rod carrying a clip and its end being shown supported so as to turn in said side-bar of the rack, and a turn-button on said side-wall of the casing supporting the said rack in an inclined position; and Fig. 4, a perspective view of one of the transverse rods of the rack, having two clips thereon, such clips supporting a card or photograph to view, as the device appears in use.

In these views, 1 indicates the base-board, 2, 2 upright side walls on said base-board, 3 a rear upright wall on said base-board, 4 a pivotal or hinged front wall filling the opening at the fore ends of said side walls, and 5 a lid

having side and end walls and hinged at its rear end to the upper edge of the rear wall 3, the whole comprising a casing or box.

A swinging rack is provided in the box, composed of side-rails 6, 6, rear cross or tie bar 7 and a series of parallel transverse bars or rods 8, the latter having their respective opposite ends mounted free to turn in sockets or openings 9 made in the inner faces of said side-rails 6, 6. The fore end of the rack is preferably made without a cross or tie bar so as to allow a space or ample room between the ends of the side-rails, the fore ends of said side-rails being pivotally-attached at 10, to the upright side-walls 2, 2, and thus adapting the rack to be swung upward at an inclination, as best seen in Fig. 1 and, also, seen in the detached view, Fig. 2.

A turn-button 11 is pivotally-attached at 12 in the countersink or recess 13 in each of the side-walls 2, 2 and is adapted to be swung inwardly to engage under the side-rail 6 at both sides of the rack so as to support the latter in an inclined position and readily operated so that said rack can be lowered into the bottom of the box when the lid is to be closed.

One or more clips or clasps 14 is rigidly mounted on each of the transverse bars 8 of the rack and each clip is composed of a thin strip of resilient or spring metal bent at its center so as to match and fit over the rod 8, the outer portions forming jaws with flaring outer ends 14^a, 14^a. The clips 14 are each preferably soldered or riveted to the respective bars 8 so that they will not slide or turn thereon and cards, photographs, or the like that are to be displayed are each inserted at their lower edges between the jaws of the 95 said clips and may be swung to and from a face view on the freely-swinging transverse supporting-rods 8.

15 indicates an inverted V-shape strip of wire pivotally-attached at its opposite ends 100 to the respective rear ends of the side-rails of the rack and adapted when swung upward and bearing against the cross-tie 7, as seen in Fig. 2, to form an easel or back-support for the cards or photographs in an inclined or canted position for display. When the box is closed, with the lid down, the cards or photographs are pivoted or turned on their respective rods 8 forward so as to fold or lap one on the other, the easel 15 turning on its 105 pivots and folding flat on the already folded photos and the turn-buttons 11 arranged so

that the rack can be dropped so as to seat in the bottom of the box. A hook 16 is provided at the fore end of the side-wall 2 and adapted to engage an eye 16^a on the lid so as 5 to hold the latter in place when closed. A hook 17 is provided on the inner face of the lid for engagement by the easel 15, as seen in Fig. 1, to hold the lid against falling further back in its open position.

- 10 The front wall 4 of the casing is swung downward and outward on its pivots so that the cards or photos on the rod at the fore end of the rack can be displayed to view without obstruction, a small card being shown in 15 dotted-lines at *c* in Fig. 1 in the position it assumes when folded down. A large card or photo C is shown in dotted-lines in Fig. 2 and it is also shown in Fig. 4, in raised position for display.
- 20 A set of four clips is shown on a number of the transverse bars at the fore end of the rack, in Fig. 1, to receive small cards or photos, a set of three clips on transverse bars at the middle of the rack for two cards 25 or photos abreast and a set of two clips on each of the rear transverse bars for single large cards or photos. The cards or photos are readily inserted in place in the clips and removed therefrom without injury thereto 30 and are housed in the cabinet ready for convenient display.

I claim:

1. A cabinet for photographs, cards, or the like, comprising a base having side and end 35 walls, a rack having side frame-bars and a rear cross-bar and pivoted at its fore end to

the said base, a series of parallel, horizontal transverse bars or rods mounted at their opposite ends in the side frame-bars of said rack, clasps or clips mounted on said transverse bars and each having outwardly-directed flaring-mouthed presser-jaws adapted to receive and hold between them one of the edges of a photo-card or the like to be housed and displayed, and means on the base adapted to be directed into and out of the vertical path of swinging-movement of said rack for supporting the latter in an inclined position for display of the photographs.

2. A cabinet for photographs, cards, or the like, comprising a base having upright side and rear walls and an outwardly-swinging front wall, a lid hinged at its rear end to the rear wall of said base, a rectangular rack pivoted at its fore end to the said base adjacent the said swinging front wall and having a series of parallel transverse bars or rods each one of which latter carries means having outwardly-directed clamping-jaws adapted to receive and hold the lower edges of the photo-card to be housed and displayed, a swinging easel mounted at the rear end of said rack and adapted to support the photo-cards in an inclined position, and means on the said base for supporting the said rack in an inclined position when swung upwardly on its pivotal fore end, substantially as set forth.

JOHN N. KOCH.
